John Hamilton
Inventor

UNITED STATES PATENT OFFICE.

JOHN HAMILTON, OF BOSTON, MASSACHUSETTS.

ELECTRICAL EXTENSION PLUG.

Application filed September 27, 1919. Serial No. 326,793.

To all whom it may concern:

Be it known that I, JOHN HAMILTON, of 140 Bellevue Street, West Roxbury Station, Boston, in the county of Suffolk and State 5 of Massachusetts, have invented certain new and useful Improvements in Electrical Extension Plugs, of which the following is a specification.

My invention comprises an improvement 10 upon what are commonly called extension plugs and which are used to enable one to easily insert into or remove from an electric circuit any special device such as a fan, portable lamp or electric toaster.

As at present used extension plugs consist 15 largely of a small annular cap of insulating material having two contact prongs or fingers which are intended to be pushed into small holes in a receptacle or fixed portion 20 which is permanently connected to the circuit wiring. Practically all of the existing extension plugs are so designed that their contact making function depends upon a pushing force required to snap the projecting 25 contacts of the cap portion into engagement with the contacts within the receptacle or fixed portion, and conversely a pull serves to separate the two portions.

Experience has shown that when using 30 devices which are connected to an electric circuit by existing extension plugs great annoyance and trouble are caused by inadvertently pulling upon the extension wires and so causing the extension plug to disengage from the receptacle and fall, and in 35 most cases in industrial plants where heavy flexible cord is used with the portable devices the weight of the cord itself is sufficient to cause the plug or cap to become disengaged; in many cases this leads to the 40 breaking and destroying of the cap or plug by the consequent fall and in every case to an interference with the operations being conducted.

The objects of my invention are to eliminate this loss and delay by making the falling out of the plug impossible; this, I accomplish by making the contact making function of my extension plug depend upon 50 a pull instead of a push consequently any strain which may be inadvertently applied to the extension wires will tend to more securely engage rather than disengage the plug or cap.

In the accompanying drawing Figure 1 55 shows a front elevation; Figure 2 shows an

end elevation and Figure 3 shows a plan; in each figure identical parts are similarly lettered and the lower or right hand end of each view is shown in section.

X is a common conduit pipe fitting such as is commonly used in all kinds of electrical installations where the wiring is installed in conduits; as commonly used X is fitted with anyone of a variety of covers each one forming a special outlet for the wires within the conduit system.

In Figures 1, 2 and 3 is shown a new design of a cover for this standard pipe fitting and this forms part of my invention; I is the integrally formed iron cover with its ends bent up into hook like formation the whole resembling the letter G of the alphabet; the cover I is attached to the pipe fitting X by the fastening screws D; into each of the hood like ends of the cover I is slipped a porcelain bushing or lining P and this is held in position by nuts recessed into the porcelain and engaging the fastening screws A which pass through the cover I.

This porcelain lining P carries at its upper end and enclosed within the projecting walls or ears of both I and P a common U shaped spring contact clip E such as is used with standard cartridge fuses; a sheet brass contact strip B is bent so as to lie within the porcelain lining P and to connect the contact clip E with the wire from within the pipe fitting X, which wire comes through a hole in the cover I and the porcelain P and is held in contact with the connecting strip B by the contact screw W. The screws C whose heads are recessed into the porcelain P engage the contact strip B (one of them passing through the contact clip E) and hold the electrical elements rigidly within the porcelain P; this description applies to either end of the cover I both ends being identical.

F is a cylindrically formed hollow contact carrier made of insulating material except that its ends are fitted with removable metal contact ferrules such as are used on the standard cartridge fuses for the purpose of engaging the spring contact clips E. In Figure 1 F is shown fitted with a hollow grip or handle of insulating material H; by taking hold of H F may be pulled against resistance into position in engagement with the spring contact clips E as shown in Figure 1 or forcibly removed therefrom.

Also in Figure 1 are shown extension wires

extending from the ferrule contacts on F through the hollow handle H to contact with terminals of lamp suitably mounted on portable handle M.

- 5 It will be noted from these illustrations that pulling upon the handle H or the portable lamp handle M or upon the extension wires connecting these two will tend to seat rather than unseat the contact carrier F.
- 10 Although I have illustrated my extension plug in combination with an incandescent electric lamp I have no intention of limiting its use to lighting but on the contrary have in mind its use for all forms of tools 15 and machinery.

Having thus fully described my invention what I claim as new and wish to protect by Letters Patent is as follows:—

1. In combination an electric conduit fitting having a removable cover formed so as to provide a hooded shelter at each end; a lining of insulating material within the hooded shelters; U shaped spring contacts mounted on the insulating linings within 25 the hooded shelters; a means for connecting wires from the inside of the conduit fitting to the U shaped spring contacts; a cylindrically formed plug fitted with a ferrule contact at each end and said ferrules adapted to snap into spring engagement with the U shaped spring contacts and to maintain this spring engagement in all possible positions of the plug; a handle mounted upon this plug and wires passing from the ferrule 30 contacts through the plug and handle to a portable translating device.

2. In combination an electric conduit fitting with its removable cover carrying concealed electric U shaped spring contacts 40 mounted in an inverted position; means for connecting wires from the inside of the conduit fitting to said U shaped contacts; an elongated tubular bridging plug carrying a ferrule contact at each end; said ferrule contacts adapted to snap by direct pressure into the spring embrace of said U shaped contacts; a lever handle mounted upon said bridging plug so as to project at right angles to its tubular axis and wires leading 45 from said ferrule contacts through said handle to a translating device substantially as shown.

3. In an electric circuit extension device a fixed portion consisting of a hollow oblong 55 casing of insulating material having a transverse section cut from its upper wall and inverted T sections cut from its side walls; a double claw shaped spring metal contact mounted in its interior at either side of the 60 opening in the upper wall; means for connecting main circuit wires to said claw shaped contacts; a movable plug portion

of insulating material having a contact fitted on each end adapted to be snapped into the embrace of said double claw shaped spring 65 metal contacts; a handle mounted upon said movable plug portion at right angles to it and so disposed that when in service it projects upwards through the opening in the upper wall of said fixed portion and 70 wires connected to the contacts on said movable portion and passing through its interior and that of the handle to a translating device substantially as shown.

4. In combination an electric receptacle 75 having U shaped spring contacts mounted on the lower side of the upper or front wall of the receptacle with their openings pointing inwardly; a tubular plug having a handle mounted upon it at right angles to its tubular axis; contacts mounted upon said tubular plug so as to engage said U shaped 80 spring contacts and wires leading from said plug contacts through said handle to a translating device substantially as shown.

5. An electric circuit extension device consisting of a fixed portion and a portable portion made of insulating material; said fixed portion fitted with spring metal contacts equipped with a means for connecting same 90 to main circuit wires; said portable portion consisting of a cylindrical plug fitted with ferrule contacts adapted to snap by a direct push or pull into or out of electrical engagement with said spring metal contacts on said fixed portion and to be revoluble through 95 180° while maintaining said electrical engagement; a handle mounted upon said portable portion and wires passing from said ferrule contacts through said handle to a translating device substantially as shown.

6. As an article of manufacture an electric circuit extension device consisting of a fixed and a movable portion both being made of insulating material; said fixed portion consisting of a hollow oblong casing with a transverse opening on its upper wall and inverted T sections cut from its side walls; spring clip contacts mounted at either side of the opening in the upper wall; means for connecting wires to said spring clip contacts; said movable portion consisting of an elongated cylindrical plug having a ferrule contact on either end and a handle projecting at right angles; said ferrule contacts adapted to be snapped into or out of engagement with said spring clips in the fixed portion by means of a direct pull or push on said handle and wires leading from said ferrule contacts to a translating device substantially as shown.

In testimony whereof I have affixed my signature.

JOHN HAMILTON.
